UNITED STATES PATENT OFFICE.

DAVID VANDERBOS, OF CHICAGO, ILLINOIS.

MUSIC-LEAF TURNER.

1,145,280.

Specification of Letters Patent. Patented July 6, 1915.

Application filed December 2, 1913. Serial No. 804,269.

To all whom it may concern:

Be it known that I, DAVID VANDERBOS, a citizen of the United States, residing at Chicago, in the county of Cook and State of Illinois, have invented new and useful Improvements in Music-Leaf Turners, of which the following is a specification.

This invention relates to music leaf turners and has for its primary object the provision 10 of a device of this character which will be applicable to portable music stands or other musical instruments, such as pianos, organs, or the like and one which may be applied to or removed therefrom with facility.

15 Another object of the invention is the provision of turning mechanism which will include companion turning arms that are adapted to be associated with the music sheets and which will be operable to present 20 to the view of the player at all times, at least two of the sheets.

Another object of the invention is the provision of actuating means which may be connected with the turning arms whereby to 25 impart movements thereto simultaneously.

A still further object of the invention is to provide turning arms which may be connected with the music sheets in such manner as to prevent derangement of the sheets during 30 the turning operation.

With these and other objects in view, the invention consists of certain novel features of construction, combination and arrangement of parts, as will be hereinafter described and claimed.

In the accompanying drawings: Figure 1 is a front view of the turning device, showing the application thereof to a portable music stand; Fig. 2 is a perspective view 40 of the supporting member; Fig. 3 is a horizontal section through the supporting member showing the turning arms applied thereto; Fig. 4 is a top plan view of the treadles and platform illustrating the manner of connection of such to the music stand; Fig. 5 is a perspective view of one of the turning arms.

While I have contemplated the provision of a music leaf turner which is designed particularly for use upon portable music stands, such as the one shown at *a* in Fig. 1 of the drawings, it is to be understood, and incident to the construction of the device that it may be readily connected with various forms of musical instruments, such as pianos, organs, or the like.

The device is shown to include a support 1 having a vertical bar 2 and a horizontal bar 3 of appropriate lengths necessary to properly accommodate music leaves of different sizes. The bar 2 is provided at suitable 60 intervals with openings 4 through which may be passed a suitable lacing or strap 5 which may be placed around and properly secured to the bars B of the rack C of the music stand, herewith illustrated. This 65 mode of connecting the member 1 to the stand is desirable in that the device is rendered applicable to portable music stands of various well known forms.

The turning mechanism comprises companion turning arms 6 and 7, each consisting of substantially U-clamping elements provided with a lower bar 8, and vertical gripping bars 9. One of the elements of each turning arm has its bar 8 hinged at 11 70 to the bar 8 of the other element, as shown in Fig. 5, while springs 12 are fitted to both elements so as to normally hold the same closed against each other, and confined against the music leaf. Through this arrangement it is seen that the music leaf may be readily arranged between the companion elements of each arm and then positively held against accidental derangement therefrom during the turning operation. The 80 bar 8 of the arm 6 is connected with the bar 8 of the arm 7 by means of a link 12' so that movement imparted directly to one of the arms will be operatively transmitted to the companion arm. The arms are normally 85 arranged side by side as clearly shown in Fig. 1 and as a consequence of this arrangement the arms are designed to accommodate themselves to sheet music which commonly consists of a cover folded to form two 90 leaves and an intermediate supplement leaf, the latter being removable ordinarily from the cover leaves. This arrangement permits at least two of the leaves of the music 95 to be displayed before the player at all 100 times. The cover page on initially arranging the music upon the arm is turned upon itself on the line of fold between the leaves numbered respectively 1 and 4 and the leaves are then placed between the companion 105 clamping elements of the arm 6. The supplement is removed, as previously described, and the opposite sides thereof are numbered respectively 2 and 3. The supplement is placed between the clamping elements of 110

the arm 7 and through the arrangement of such arm 7 with the arm 6 it is apparent that on the first playing of the music the sheets numbered 1 and 2 will be exposed. 5 One of the gripping elements of each turning arm is pivoted at 13 to the bar 3. The actuating means whereby the arms 6 and 7 may be turned simultaneously and in the required order to a successive arrangement of 10 the numbers of the music sheets, comprises a small flexible chain 14 or the equivalent thereof. The chain is passed over suitable guides 16 on the bar 3 and the terminals 15 are connected to the ends of the link 12', while the terminals 16 and 16^a are extended downwardly and then connected at 17 with foot treadles 18 and 19. These treadles are pivoted to a suitable platform 19 mounted on an attaching bracket 23. In further 20 describing the operation, it is assumed that the arms 6 and 7 are in positions to properly display the sheets numbered 1 and 2 and that the treadle 18 is elevated, while the treadle 19 is lowered. When it is desired 25 to reverse the arrangement of the turning arms so that the sheets numbered respectively 3 and 4 will be brought to view, the treadle 18 is depressed by the foot with a resulting pull upon the branch 16 of the chain. The movement of the chain as specified causes the arm 6 to be moved and as a consequence of such movement and through

the link 12', the arm 7 will be correspondingly moved as will be appreciated.

From the foregoing description, taken in 35 connection with the accompanying drawings, the construction and operation of the invention will be readily understood without requiring a more extended explanation.

Various changes in the form, proportion 40 and the minor details of construction may be resorted to without departing from the principle or sacrificing any of the advantages of this invention as claimed.

I claim:—

45 A music leaf turner having a support including an apertured horizontal portion and an apertured vertical portion, a rack, means passing through the apertures of the vertical portion and having connection with the rack for removably securing the latter to the former mentioned portion, a pair of turning arms journaled in the openings in the horizontal portion of the support, means having connection with the turning arms for causing a simultaneous turning of said arms, and operating means having connection with the latter mentioned means.

In testimony whereof I affix my signature in presence of two witnesses.

DAVID VANDERBOS.
